UNITED STATES PATENT OFFICE.

PERLEY R. GLASS, OF BROOKLINE, MASSACHUSETTS, ASSIGNOR TO UNITED SHOE MACHINERY COMPANY, OF PATERSON, NEW JERSEY, A CORPORATION OF NEW JERSEY.

FASTENER-SETTING MACHINE.

1,228,768.

Specification of Letters Patent.

Patented June 5, 1917.

Application filed August 5, 1914. Serial No. 855,185.

To all whom it may concern:

Be it known that I, PERLEY R. GLASS, a citizen of the United States, residing at Brookline, in the county of Norfolk and 5 Commonwealth of Massachusetts, have invented certain Improvements in Fastener-Setting Machines, of which the following description, in connection with the accompanying drawings, is a specification, like 10 reference characters on the drawings indicating like parts in the several figures.

This invention relates to improvements in machines for setting fasteners in sheet material, and more particularly to machines 15 for inserting such fasteners as eyelets or lacing hooks in the uppers of boots and shoes.

In setting eyelets of various sizes and in 20 different styles of boots and shoes a wide variation in spacing is demanded; for example, small eyelets are often set in women's shoes with a spacing of one half inch or less, while large eyelets are often set in heavy boots with a spacing as wide as two inches. 25 The feeding mechanism of eyelet setting machines as heretofore constructed has operated at a uniform speed regardless of the extent of the feeding steps, and consequently the linear speed of the work through the 30 machine has varied very greatly. This has frequently resulted in wasted time in the former case, and in inconvenience to the operator and work of poor quality in the latter case, for it has been impractical to 35 vary the speed of the machine in accordance with the setting of the feeding mechanism.

In the case of a machine running at the proper speed for eyelets set with a wide spacing, the setting of eyelets with a close 40 spacing has resulted in a very slow travel of the work through the machine, while, on the other hand, in the case of a machine operating at the proper relatively high speed for eyelets set with a close spacing, 45 an unmanageable speed of the work has resulted when the spacing mechanism has been adjusted for wide spacing.

With these conditions in view, an important feature of the present invention consists broadly in variable or change speed 50 mechanism and adjustable work feeding means controllably related in respect to its adjustment, to said mechanism. The em-

ployment of such mechanism enables the work to be passed through the machine at 55 a substantially uniform linear speed regardless of the spacing of the fasteners or eyelets; for example, if two-speed mechanism were arranged to operate the machine at either 600 or 350 revolutions per minute a 60 substantially uniform movement of the work through the machine would result when setting eyelets with a three-quarter inch spacing at the rate of 600 per minute, or, when setting eyelets with a spacing of one and 65 one-quarter inches at the rate of 350 per minute.

In this connection another feature of the invention consists in means for locking the feed controlling device against movement to 70 position corresponding to a wide spacing so long as the change speed mechanism is arranged to operate at the higher speed. As another feature of the invention it is contemplated that the spacing and speed 75 controlling mechanisms shall be so related that the speed controlling device will be prevented from movement to its position for high speed so long as the spacing mechanism is set for wide spacing. Such construction safeguards both the machine and the operator against the results of the unexpected operation of the machine at excessive speed.

Other features of the invention consist 85 in the novel construction and arrangement of the moving parts, whereby inertia is reduced to a minimum and operation of the machine at a high speed, together with positive and accurate starting and stopping, 90 rendered possible. These constructional features will be pointed out in detail hereinafter, but may be grouped for convenience as follows: (1) mechanism for operating the lower or eyelet carrying set, (2) mechanism for raising and lowering the up-setting and punching tool, (3) mechanism for transversely moving one of the tools for feeding the work, (4) raceway operating mechanism, (5) presser foot operating mechanism, 100 and (6) gage mechanism. While each of these several features is believed to possess many novel characteristics their coöperative combination also involves subject matter of invention.

These and other features of the inven-

tion will be best understood and appreciated from the following description of a preferred embodiment thereof selected for purposes of illustration and shown in the 5 accompanying drawings, in which,—

Figure 1 is a view of the machine in side elevation with parts of the frame broken away;

Fig. 2 is a view of the machine in front 10 elevation;

Fig. 3 is a view in perspective of the mechanism for operating the setting devices;

Fig. 4 is a fragmentary view of a portion 15 of the spacing mechanism;

Fig. 5 is a view in perspective of the mechanism for operating the lower setting device;

Fig. 6 is a fragmentary view in perspective 20 of the raceway and its operating mechanism;

Fig. 7 is a view in perspective showing from the rear certain parts illustrated in Fig. 3;

Fig. 8 is a diagrammatic plan view of the 25 spacing mechanism; and

Fig. 9 is a view in perspective of the gage mechanism.

The machine frame 2 is suitably shaped 30 to support the moving parts of the machine and is provided with journals for the main shaft 4 carrying at one end a driving pulley 3. A clutch mechanism of well known type is interposed between the pulley 3 and the 35 main shaft and the starting and stopping of the machine is controlled through this mechanism.

Lower setting tool.—The lower portion of 40 the frame is provided with vertical guideways in which reciprocates the plunger 6 having adjustably mounted in its upper end the lower or eyelet carrying set 9. Secured to the plunger 6 is a split collar 8 having ears on its rear side through which extends a 45 clamping bolt. This bolt is extended beyond the ears of the split collar and forms the journal for a block 10 which is held in place by a washer 12 shown in Fig. 3. The block 10 is received between the jaws of a forked 50 lever 14 journaled between its ends upon a shaft 16 which is suitably supported by the machine frame. The lever 14 is oscillated by a connection with a crank 22 fast on the main shaft 4 as shown in Fig. 5. This 55 crank has pivotally secured to its outer end a follower comprising a block 20 of which the upper and lower surfaces are curved to slide in a curved slot 18 formed in the rear end of the lever 14.

60 From the mechanism thus far described it will be apparent that the rotation of the main shaft 4 imparts vertical reciprocations to the eyelet carrying set 9. The curvature of the slot 18 in the lever 14 is on a radius 65 slightly longer than the length of the crank

22, and when the shaft 4 is rotated, the block 20 moves forwardly in the slot and imparts a slow upward movement to the eyelet carrying set 9 during the first quarter of the revolution of the shaft. When this movement has taken place the crank 22 has reached such a point that the next quarter revolution of the shaft depresses the rear end of the lever 14 very rapidly, and this motion effects a rapid elevation of the eyelet 70 carrying set 9 after the raceway has been withdrawn. In the next half revolution of the shaft the eyelet carrying set is lowered, at first rapidly and then more slowly, and the parts are returned to their initial positions, as shown in Fig. 5.

The construction of the mechanism for operating the eyelet carrying set is particularly advantageous in that it affords simple and positively acting means for moving the 75 set in the desired manner, that is to say slowly upwardly until an eyelet has been delivered from the raceway, then rapidly upwardly to effect the clenching operation and then downwardly at high speed so that the 80 work is disengaged and left free to be advanced at the earliest possible moment in the cycle of the machine.

The split clamping collar 8 affords facility 85 for making a preliminary adjustment of the path of movement of the setting tool 9, but in order to enable the operator to make the adjustments necessary from time to time in running the machine an adjusting bolt 11 is threaded into the bottom of the plunger 6 and by turning this bolt the position of the setting tool in its carrying plunger may be 90 varied.

Upper setting tool.—The frame 2 is formed with an overhanging portion having two 105 sets of horizontal bearings, one for the upper rod 26 which is held stationary by screws 30, and the other for the lower rod 28 which is arranged to slide freely in its bearings. The horizontal rods 26 and 28 110 carry the feed frame 32. At its upper end the feed frame is free to slide upon the rod 26 while at its lower end it is secured to the rod 28 and carries the latter with it in its transverse movements for feeding the work. 115 The feed frame 32 is provided with vertical guideways for the plunger 34 which carries at its lower end the combined punching and upsetting tool 40. The plunger 34 is moved downwardly to punch the work, then elevated slightly to relieve the pressure on the cutting block while in punching position and is moved slightly downwardly again and then upwardly while in setting position. 120 These vertical movements are effected 125 through mechanism which will now be described. A collar 36 surrounds the plunger 34 and rests upon an adjustable nut 38. At either side of the collar are pivoted links 42 130 which constitute the lower member of a

toggle of which the upper member comprises a pair of bell crank levers 44 journaled at their upper ends about the stationary rod 26 and connecting the knuckle of the toggle with the forward end of a link 48. The link 48 has formed in it an inclined slot 50 through which loosely extends the stationary pin 52. The slot 50 acts as a guide for the end of the link 48 and throws the latter slightly up and down as it is reciprocated from front to rear, keeping its end substantially opposite to the knuckle joint of the toggle as the latter is straightened and broken. The link 48 is connected 15 at its rear end to the upper end of a vertically disposed cam lever 54 as shown in Fig. 7. The lever 54 is journaled upon a stationary pin 56 and at its lower end has two forked arms upon the inner surfaces of 20 which are secured hardened bearing pieces. A cam 58 secured to the shaft 4 acts upon these bearing pieces and thus oscillates the lever.

The link 48 is so connected with the toggle 42-44 as to permit the relative transverse movement to take place which is necessary in the feeding operation. To this end it has rigidly clamped in its forward end a transversely disposed rod 43 upon which 30 slide the rear ends of the two bell crank levers 44. The forward end of the link 48 is held against transverse movement by heads formed on the pin 52. This feature is of importance in that it prevents all binding 35 or cramping of the levers 44 upon the rod 43, a difficulty which would occur if the link 48 were permitted to become angularly displaced.

Work feeding mechanism.—Transverse movement is imparted to the tool 40 for feeding the work by mechanism which will now be described. The frame 32 is provided at its lower end with a rearwardly extending arm to which is pivotally secured the block 45 80. The block 80 is received between the jaws of a forked arm 82 journaled upon a stationary vertical shaft 86. Below the hub of the arm 82 there is journaled a sleeve 88 which has a forwardly extending projection 50 beneath the arm 82 and has an upstanding ear located on each side of the arm. Oppositely disposed set screws are threaded into 55 the ears of the member 84 and bear against the sides of the arm 82 and by turning these set screws in the appropriate direction the initial position and transverse path of the frame 32 may be adjusted. The rear end of the arm 82 is formed as a split clamp by which the arm is clamped to the upper end 60 of the sleeve 88.

The arm 90 is pivotally secured at its outer end to a link 92 which, in turn, is pivoted to the forward end of a link 94. At its rear end the link 94 is pivotally secured to the upper 65 side of a yoke frame 98 guided in horizontal

ways for movement from front to rear. The frame 98 has extending from its lower side a pair of jaws fitted with hardened bearing pieces which engage a cam 100 upon the main shaft 4. The path of the point of pivotal connection between the links 92 and 94 is guided by a pair of radius links 96 secured to a sleeve 102 journaled upon a vertical pin 104 which is set in the under side of a pivoted plate 106. The plate 106 is arranged 70 to turn about a pivot pin 108, as shown in Fig. 8, and is provided with a spacing handle 109 which swings over a graduated spacing plate 110. The plate 106 has an upwardly extending boss to which is secured a spring 112 fast at its other end to a pin projecting from the machine frame. The spring holds the spacing lever 109 in an initial position 75 against one of two stops 114.

Through the connections above described 80 the uniform reciprocation of the yoke frame 98 is transmitted to the feed frame 32 and so long as the spacing lever 109 remains in the same position the extent of feeding movement will be uniform. The extent of the feed, and consequently the spacing of the eyelets, is controlled by this lever. To increase the feed the lever is moved forwardly as shown in Figs. 3 and 8. This movement of the lever 109 carries the pin 104 into such 85 position that the path of movement of the point of pivotal connection between the two links 92 and 94 is varied and a greater component of movement of the yoke frame 98 is transmitted to the sleeve 88. When the spacing handle 109 is in the full line position shown in Fig. 8 the oscillation of the sleeve 88 is represented by the angle A. When the spacing handle is moved to the 90 dotted line position shown in Fig. 8, the oscillation of the sleeve 88 is increased to the angle B. 95

Raceway mechanism.—Eyelets are supplied to the spindle of the eyelet carrying set 9 by the raceway 120 removably carried 100 by the bracket 122 pivotally mounted upon a shaft 124 set in the machine frame 2. When the eyelet carrying set is in its initial position, the delivering end of the raceway holds its endmost eyelet in a position slightly above and in the rear of the end of the spindle. When the machine is started the raceway is first oscillated so as to carry the eyelet into position to be engaged by the spindle, whereupon the delivery end of the raceway 115 is moved rearwardly into an inoperative position, thus allowing the passage of the eyelet carrying set. 120

Movement of the raceway is effected from a crank 136 on the end of the main shaft 4. 125 The crank 136 is connected through a short link 134 with a pivot on a downwardly extending arm 132. At its lower end the arm 132 is connected through a universal joint to an adjustable pitman 130 which, at its for- 130

ward end, is similarly connected to one arm of a bell crank lever 128 journaled upon a vertical pin set in the machine frame. The other arm of the bell crank lever 128 is connected through a short link 126 to a projection upon the raceway bracket 122.

It will be noted that the end of the raceway is moved rearwardly from its delivering position instead of outwardly as heretofore.

10 This arrangement is particularly advantageous in that it obviates all possibility of injury to the operator, there being no possibility of accidentally reaching the space between the end of the raceway and the machine frame.

15 The raceway itself carries at its upper end a hopper 121 of the usual construction, and this and the raceway are removably held in place on the bracket 122 by a hand nut 119 which may be readily loosened whenever it is desired to change from one style of eyelet to another. The hopper is provided with an agitator of the usual form, which is driven by the pulley 123 through a belt running about a pulley formed on a cap 125 located on the right hand end of the main shaft 4, as seen in Fig. 2. The cap 125 may be clutched to or unclutched from the loose driving pulley 3 by means of a shifting arm 25 127 pivotally mounted on a stationary casting 129.

30 The machine is provided with a work table 71 of suitable shape to accommodate the work to be eyeleted. The table is perforated to permit the passage of the lower setting die, and slotted to receive a cutting bed or block 69 with which the punching end of the tool 40 co-operates in performing the work.

35 *Presser foot mechanism.*—A presser foot 72 is arranged to clamp the work on the work table between the feeding operations of the machine. The presser foot is adjustably clamped to the upper end of a vertical rod 70, to which is secured a block 68 carrying a roller 66, by which the presser foot is intermittently elevated. A compression spring resting upon the block 68 holds the presser foot normally in clamping position with the roller 66 resting upon the periphery of an oscillatory cam plate 64, best shown in Fig. 7. The cam plate 64 is mounted to oscillate about a horizontal axis, and is actuated by the movement of the cam lever 54 which, it will be remembered, actuates also the toggle mechanism of the upsetting tool. One jaw of the cam lever 54 is provided with an extension 60 which is connected to the cam plate 64 through a rod 62 45 having a split clamp at each end. It will be seen that when the upper end of the cam lever 54 is thrown forwardly to depress the tool 40 the extension 60 is moved rearwardly and the cam plate 64 turned to such position 55 that the roller 66 and the presser foot 70

will be elevated to release the work. The lower end of the presser foot rod 70 extends through bearings in the machine frame into engagement with the forward end of a treadle actuated lever 74 which may be elevated through the chain 76 when it is desired to raise the presser foot to permit the presentation of work to the machine. To prevent the presser foot from being displaced angularly, a parallel pin 75 is connected to the bar 70, and by sliding in a hole in the frame prevents twisting of the bar.

60 *Gage mechanism.*—In order to determine the spread of the eyelets or their distance from the edge of the lacing slit, a gage 160 is arranged at a point in the rear of the cutting bed 69. The gage 160 is adjustably secured to the end of a gage carrying arm 162 which is pivotally mounted at the right hand end of the work table for movement from front to rear. The pivot pin 164 of the gage carrying arm extends through the table 71 and is threaded at its lower end to receive a nut having a clamping handle 166. By this construction a convenient means is afforded for adjusting the gage 160 into any desired position. It may be moved transversely on the gage carrying arm 162 or it may be moved from front to rear by loosening the 65 clamping nut and swinging the gage carrying arm to the desired position where it may be locked by a slight movement of the handle 166.

65 *Speed controlling mechanism.*—Below the machine frame is disposed a countershaft 140 journaled in a bracket member 141 and carrying a small driven pulley 144 and a large driven pulley 146 which are constantly rotated in the same direction but at different rates of speed. The countershaft 140 also carries a driving pulley 142 which is belted directly to the pulley 3 on the main shaft of the machine, as shown in Fig. 1. The hubs of the pulleys 144 and 146 are each 70 provided with a clutch surface shaped to correspond with the opposite surfaces of a fast clutch member 148 splined to the countershaft 140. A clutch shifting lever 150 is disposed within convenient reach of the operator, and by it the clutch member 148 may be connected to either one of the driven pulleys 144 or 146, so that the machine will be operated at a greater or lesser speed in accordance with the requirement of the work 75 in hand.

80 The transmission mechanism above described is so related to the spacing mechanism of the machine that operation at high speed is permitted only when the spacing mechanism is set for a short feed, operation at low speed being desirable when the machine is set for a wide spacing. To this end the clutch controlling lever 150 is provided with an inclined cam surface 152 so disposed 85

as to elevate an adjustable rod 154 whenever the handle 150 is moved toward the right, as shown in Fig. 3, or into the position corresponding to high speed. The pivoted spacing plate 106 is provided in its periphery with a tooth which, in the position of the parts illustrated, stands at one side of the upper end of the rod 154, but which, when the spacing lever 109 is moved to a position corresponding to a wide spacing of the machine, stands over the end of the rod 154 and locks it against vertical movement. With the parts in the positions shown in Fig. 3 the spacing lever 109 is set for a feed of about three-quarters of an inch, and the clutch controlling handle 150 is free to be moved into either position, so that the machine may be run at a high speed. When the spacing handle 109 has been moved forwardly to increase the feed of the machine the rod 154, as above explained, prevents the movement of the clutch controlling lever 150 toward the right, and so prevents the machine from being run at high speed with a wide spacing. Moreover, if the clutch controlling lever 150 is moved to engage the smaller or high speed pulley 144 while the spacing lever 109 is in a position corresponding to a short feed, the end of the rod 154 will stand in the path of the tooth on the spacing plate 106, and so prevent the spacing handle 109 from being moved forwardly to increase the feed of the machine.

The operation of the machine which, it is believed, will be readily understood from the foregoing description is briefly as follows:—The position of the gage 160 and the feed of the machine are initially established, and the speed of the machine is appropriately regulated by the setting of the clutch controlling lever 150. The work to be eyeleted is then presented upon the work table with the point at which the first eyelet is to be set located under the tool 40 which initially occupies its extreme right hand position. The machine is then started, whereupon the toggle 42—44 is straightened, depressing the tool 40 and perforating the work. The knuckle joint of the toggle is carried slightly past its central position so that the tool 40 is elevated sufficiently to carry its end out of engagement with the cutting bed, and relieve the pressure of the machine. The feed frame 32 is then moved toward the left carrying the tool 40 into alignment with the eyelet carrying set 9 which takes an eyelet from the raceway and then moves upwardly to effect the inserting and clenching operations. Immediately thereafter the toggle 42—44 is broken and the tool 40 elevated out of engagement with the clenched eyelet, the work meanwhile being clamped by the presser foot which holds it stationary while the setting devices are returned to their initial positions.

Having now described my invention, I claim as new and desire to secure by Letters Patent of the United States:—

1. A machine for setting fasteners, having in combination, adjustable work feeding and fastener inserting means, and variable speed transmission mechanism limited as to its effective speed by the adjustment of the work feeding means. 70

2. A machine for setting fasteners, having in combination, work feeding and fastener inserting means, feed regulating means, and change speed mechanism controllably related to said regulating means. 75

3. A machine for setting fasteners, having in combination, work feeding means, a regulating device therefor, and means for controlling the speed of the machine in accordance with the setting of said regulating device. 80

4. A machine for setting fasteners, having in combination, means constructed and arranged to feed the work intermittently variable distances in accordance with the will of the operator, and means for increasing the speed of the machine as the extent of the feeding steps is decreased. 85

5. A machine for setting fasteners, having in combination, work feeding means constructed and arranged for adjustment 95 for varying the spacing of the fasteners, and speed controlling means constructed and arranged to maintain the speed of the work through the machine substantially uniform while the fasteners are set at different spacings. 100

6. A machine for setting fasteners, having in combination, change speed mechanism, and adjustable work feeding means controllably related, in respect to its adjustment, to 105 said mechanism.

7. A machine for setting fasteners, having in combination, change speed mechanism, adjustable work feeding means, and a regulating device therefor controllably related 110 to the change speed mechanism.

8. A machine for setting fasteners, having in combination, change speed mechanism, a controlling device therefor, work feeding means, a movable regulating device for said means, and a position determining connection between said two devices. 115

9. A machine for setting fasteners, having in combination, change speed mechanism, adjustable work feeding means, and means for preventing operation of the machine at the higher speed when the feeding means are set for wide spacing. 120

10. A machine for setting fasteners, having in combination, adjustable work feeding means, change speed mechanism, and means for preventing the feeding means from being adjusted for wide spacing when the machine is being operated at the higher speed. 125

11. A machine for setting fasteners, hav- 130

- 5 ing in combination, adjustable work feeding means, a lever movable for regulating the action of the feeding means, change speed mechanism, and a stop constructed and arranged to be moved into or out of the path of the regulating lever in accordance as the change speed mechanism is set to operate the machine at its higher or lower speed.
12. A machine for setting fasteners, having in combination, change speed mechanism, a controlling lever therefor, adjustable work feeding means, and a stop constructed and arranged to be moved into or out of the path of the controlling lever in accordance as the feeding mechanism is set for 10 close or wide spacing.
13. A machine for setting fasteners, having in combination, relatively movable setting tools, a lever for operating one of the tools having a curved slot near one end, a curved block slidably fitted in said slot, and crank operating connections for the block.
14. A machine for setting fasteners, having in combination, relatively movable setting tools, an operating shaft having a crank, a tool operating lever constructed and arranged to swing from one side to the other of the axis of the shaft and having a curved elongated slot, and a curved block disposed 15 within the slot and connected to the crank.
15. A machine for setting fasteners, having in combination, a movable setting tool, toggle links for operating the tool, a cam lever having a link connection with the joint of the toggle, and means for guiding the end of the link adjacent to the toggle.
16. A machine for setting fasteners, having in combination, a reciprocator setting tool arranged for transverse movement to feed the work, toggle links for operating the tool constructed and arranged to move transversely therewith, and a link for operating the toggle, said link being slidably connected to the toggle and being held against 20 transverse movement at its operating end.
17. A machine for setting fasteners, having in combination, a reciprocator setting tool, a transversely movable carriage for the tool, toggle links connected at one end to 25 the carriage and at the other to the tool, said links being bodily movable transversely with the carriage, an operating link carrying a cross pin to which the joint of said toggle is slidably connected, and means for preventing transverse movement of the link.
18. A machine for setting fasteners, having in combination, a reciprocator tool having a carrier with an adjustable sleeve, an operating toggle comprising double links 30 secured to the sleeve and double bell crank levers connected to the links, and cam operated means for straightening the toggle.
19. A machine for setting fasteners, having in combination, a work feeding tool, a 35 frame constructed and arranged to be reciprocated in a straight path, a rocker member for moving the feeding tool transversely, a pair of links connected end to end and interposed between the frame and the rocker member, and means for regulating the path of movement of the point of pivotal connection of said links to determine the extent of the feed.
20. A machine for setting fasteners, having in combination, a work feeding tool, a 40 rocker member arranged to be oscillated in the work feeding operation, and an arm pivoted for movement about the axis of the rocker member and having adjustable connection with said member.
21. A machine for setting eyelets, having, in combination, an eyelet carrying set, and a pivotally mounted raceway constructed and arranged to deliver eyelets to the set and being movable toward and from an inoperative position in the rear of the set, the axis of the raceway being so located that the movement of the delivery end of the raceway takes place in a path at substantially right angles to the path of the eyelets along the 45 raceway.
22. A machine for setting fasteners, having in combination, a pivotally mounted raceway, an arm arranged to swing about an axis at right angles to the axis of the raceway, an operating crank connected to the arm between its ends, and connections for actuating the raceway interposed between the free end of the arm and the raceway.
23. A machine for setting fasteners, having in combination, a pivotally mounted raceway, a bell crank lever connected to the raceway adjacent to its delivery end, a cam actuated arm arranged to swing about an axis at right angles to that of the bell crank 50 lever, and an adjustable link interposed between said arm and the bell crank lever.
24. A machine for setting fasteners, having in combination, coöperating setting tools, a cam lever for operating one of the tools, a 55 movable presser foot, and direct connection between said cam lever and presser foot for moving the latter in a direction opposite to the movement of the tool.
25. A machine for setting eyelets, having, in combination, an eyelet set, a raceway mounted for movement about an axis parallel to the set, a lever 128 pivotally mounted for movement about an axis located adjacent to the delivery end of the raceway and 60 connected to the raceway, and mechanism acting through the lever 128 to move the raceway to and from eyelet delivering position.
26. A machine for setting fasteners, having in combination, a movable fastener carrying tool, an oscillatory raceway for supplying the same, and an actuating shaft having a pair of cranks set in substantially 65 opposite directions, a lever interposed be-

tween the tool and one crank, and independent connections interposed between the raceway and the other crank.

27. In a machine for setting fasteners, a tool operating mechanism including a tool carrying lever movable in a predetermined plane and having a curved slot, a crank rotatable in a parallel plane, and a follower connected to the crank and arranged to slide in the slot of the tool carrying lever and to swing the lever.

28. A machine for setting fasteners, hav-

ing, in combination, a frame, a reciprocating setting tool; toggle links for operating the tool, and an operating link connected to the joint of the toggle, said frame and link having one a slot 50 and the other a stud 52.

In testimony whereof I have signed my name to this specification in the presence of two subscribing witnesses.

PERLEY R. GLASS.
